WELL FLUID FLOW CONTROLLING DEVICE

Jeddy D. Nixon, Houston, Tex., assignor of one-half to Wilson Supply Company, Houston, Tex., a corporation of Texas

Application December 30, 1940, Serial No. 372,238

13 Claims. (Cl. 103—231)

This invention relates to new and useful improvements in well fluid flow controlling devices.

This application involves certain improvements upon the apparatus set forth in my co-pending applications, Serial No. 304,684, filed November 16, 1939; and Serial No. 322,065, filed March 4, 1940.

One object of the invention is to provide an improved well flowing device including a spring-impelled valve operating member arranged to be held out of valve operating position by a weight bar, whereby said member is released when the bar is lifted and automatically actuates the valve to admit lifting fluid.

An upwardly flowing column of fluid exerts a lifting action on any member suspended therein due to what is termed "skin friction" which is the tendency for the flowing fluids to cling to the body suspended therein and this is true where a weight bar is suspended on a wire line in a well to operate a valve either of the type shown in my Patent No. 2,171,480, or of the type shown in my co-pending application, Serial No. 322,065. Due to the fact that all the lifting fluid and well fluid expelled from the well must pass through the tubing around the weight bar, the skin friction of said weight bar together with the high speed of the travel of said fluid will pick up or lift said bar and this lifting action together with the tension in said wire line will lift said bar from about a few inches to possibly several hundred feet. Also, the pressure or velocity of the fluid may be sufficient to only pick up said weight bar a very slight distance before the weight of the bar returns it to its original position and this action will give a bouncing or rapid reciprocation of said bar which is very fatiguing to the line as well as has a tendency to kink or unnecessarily bend said wire, which brings about strain, damage and final breaking thereof. Further, this bouncing or rapid reciprocation of the bar causes pounding thereof on the valve which will damage said valve, as well as the lower end of said bar, loosen the threaded connections of the bar and may even uncouple said threaded joints. Of course, any damage or breakage to the valve, wire line, or excessive damage to the bar, or the uncoupling of said bar will necessitate the removal and replacement or repair thereof. In such a case to remove these elements it becomes necessary to pull the tubing and whenever it becomes necessary to remove the tubing from the well, it always requires special equipment and additional labor and expense to the proper operation of the well, as well as loss of production, all of which increases the well overhead and reduces the returns had from the well.

An important object of the invention is to provide an improved lifting fluid inlet valve and actuating means therefor so arranged that the

actuating means may be releasably attached to the operating element of said valve, whereby said actuating means is connected to said valve but may be readily released or disconnected therefrom when and as often as desired.

Another important object of the invention is to provide an improved lifting fluid inlet valve and actuating means therefor so constructed that when said actuating means is operating or in an operating position on said valve, said means is releasably connected to the operating element of said valve, whereby when said means is moved to actuate or open said valve, the upwardly flowing well and lifting fluid will not pick up or have a tendency to carry said actuating means therewith.

It would be impractical to make a positive connection of said weight bar to said valve without allowing adjustment for any inaccuracies of the surface operating mechanism and for stretch of said wire line, which wire line may be from a few hundred feet to many thousands of feet long, and also temperature changes affecting said wire line. Also, this adjusting means should be substantially automatic so as to take care of any of these conditions as they arise after said weight bar is connected to the valve.

A further important object of the invention is to provide an improved connecting means on the lower end of an actuating member which is so arranged that while the actuating member may be connected to the valve until it is desired to release the same, that an automatic adjustment is obtained, whereby the connection has sufficient flexibility as to compensate for any inaccuracy in the operation of the wire line support for said actuating member, temperature conditions in the well, or other circumstances which would disengage said actuating member from the fluid inlet valve or place an unnecessary strain on the wire line if this connection was positive and rigid.

A further object of the invention is to provide improved means for releasing trapped lifting fluid and free gas when the operating member is depressed to permit the inlet valve to close; said means being arranged to close when the inlet valve is opened.

A particular object of the invention is to provide an improved pressure fluid inlet valve and operating means therefor which are so constructed that a free-acting and substantially trouble-free flow controlling device is provided, whereby all previous difficulties encountered by a device of this type are eliminated and overcome.

A further object of the invention is to provide an improved well flowing device having a lifting fluid inlet and closure means therefor, together with means for normally holding the closure means open and operable from the surface of the well to release said closure means, whereby the

lifting fluid will actuate the closure means and shut off the admission of lifting fluid.

A construction designed to carry out the invention will be hereinafter described, together with other features and objects of the invention.

The invention will be more readily understood from the following specification and by reference to the accompanying drawings, in which an example of the invention is shown, and wherein:

Figure 1 is a view partly in section and partly in elevation, of the upper portion of a well;

Figure 2 is a continuation of Figure 1, showing the middle portion of a well, and a valve and actuating member therefor constructed in accordance with the invention, mounted therein;

Figure 3 is a continuation of Figure 2, showing the lower portion of the well;

Figure 4 is an enlarged detailed view, showing the upper portion of the flow device in an open position and with the actuating bar disengaged therefrom;

Figure 5 is a continuation of Figure 4, showing the middle portion of said device;

Figure 6 is a continuation of Figure 5, showing the lower end of said device;

Figure 7 is an isometric view of the upper slips forming the upper part of the clutch member in the lower end of the actuating bar;

Figure 8 is a similar view showing the lower slips which form the lower portion of said clutch member;

Figure 9 is an enlarged, detailed view showing how the operating bar is attached to said flow device;

Figure 10 is a similar view showing the operating bar in its lower position and the flow device in its closed position;

Figure 11 is a horizontal, cross-sectional view taken on the line 11-11 of Figure 5;

Figure 12 is a similar view, taken on the line 12-12 of Figure 10;

Figure 13 is a longitudinal, vertical view taken through the clutch member;

Figure 14 is a horizontal, cross-sectional view taken on the line 14-14 of Figure 4;

Figure 15 is a horizontal, cross-sectional view taken on the line 15-15 of Figure 13; and

Figure 16 is a similar view taken on the line 16-16 of Figure 13.

In the drawings, the numeral 20 designates the usual well casing (Figures 1, 2 and 3) which has a well tubing string 21 depending axially therethrough. The upper end of the casing is screwed into the usual casing head 22, mounted upon the ground level, and the upper end of the tubing string is supported within the casing head in the regular manner. All of the aboveground structure may be substantially the same as that set forth in any of my Patents Nos. 2,171,478; 2,171,812 and 2,202,462; and my above-mentioned co-pending applications, as well as my co-pending application, Serial No. 337,048, filed May 24, 1940, or any structure desired; although such structure has not been shown and forms no part of the present invention.

The tubing string 21 may extend substantially the full length of the casing 20, and its lower end may terminate within the lower portion of said casing, or it may extend below said casing to within a short distance of the bottom of the well at some distance below the lower end of said casing. A suitable liner 23, either perforated or plain, may be provided on the lower end of said casing, or the lower portion of the well bore below said casing may be open or uncased. The

lower end of said tubing 21 may terminate within said casing, or in said liner, or in said uncased portion of said well bore, or below said liner; and preferably a suitable screen or bull plug 24 is provided on the lower end of said tubing string. The usual standing or foot valve 25 is mounted within the lower end of said tubing above the bull plug 24.

The tubing string 21 is preferably provided with a number of flow or kick-off valves 26, intermediate its ends and in spaced relation to the standing fluid level of the well, as pointed out in my above-mentioned patents and co-pending applications. The construction of these flow valves may be the same as that taught in my Patent No. 2,171,480, or any other structure suitable for the purpose. These valves serve to lower the well fluid level in said casing 20 and in said well tubing 21 down to the point or level at which it is desired to operate or produce the well. In some instances, one of or substantially the same flow valve is used as a producing or operating valve, but in other wells where it becomes necessary to produce said well fluid at a point below the end of said casing string 20, or in the liner 23 mounted in the lower end of said casing, or below a perforated portion of said casing string, or of said liner, the usual kick-off valve 26 or producing valve may not be used at this point. Therefore, it is necessary to set a packer 27, preferably of my own construction such as is shown in my Patent No. 2,171,479, although any desired packer or other seal-off device may be used. It is preferred to mount the packer 27 in said tubing string and to set said packer as low in said casing string as is possible, in accordance with the position of said liner 23 or of the above-mentioned perforations (not shown).

An elongate, cylindrical valve 28 is mounted in said tubing just above said packer 27 and while at first glance this valve seems to differ somewhat from my usual kick-off valves, its basic principle of action is the same. This valve 28 is very similar in action and construction to the valve shown in my co-pending application, Serial No. 322,065. The upper end of said valve 28 is provided with a cylindrical collar or cap 29 having an internally screw-threaded box 30 on its upper end for receiving a depending, externally screw-threaded, pin 31 of said tubing 21 for connecting the upper end of said valve into said tubing string. The lower end of said cap 29 is provided with a box 32, similar to said box 30, for engaging an upstanding, externally screw-threaded, pin 33 on the upper end of an upper valve body or head 34. The lower portion of this body is provided with an externally screw-threaded pin 35 for receiving an internally screw-threaded box 36 upon the upper end of an elongated, cylindrical sleeve 37 and this sleeve has a similarly threaded box 38 on its lower end for receiving one end of an externally screw-threaded lower body or cross plug 39. A cylindrical collar 40, similar to the collar 29, is threaded onto the lower portion of said cross plug 39 and has an internally screw-threaded box 41 on its lower end for receiving the threaded pin 42 on the upper end of a portion of said tubing string to connect the lower portion of said tubing to said valve 28. A relatively soft metal packing ring 43 is inserted between the upper end of said upper valve body 34 and the lower end of said collar 29, between the lower end of said body and the upper end of said sleeve 37, and between the lower end of said sleeve and the upper end of

said collar 40 for sealing these joints and connections to prevent leakage at said connections. Thus, it will be seen that said valve 28 may be readily connected in said tubing string.

The upper valve body 34 is provided with an internal cylindrical chamber 44. A plurality of radial internally screw-threaded ports 45 extend outwardly through the walls of said body from said chamber and provide communication between the annular space within said casing and said tubing string through said chamber 44. When said ports 45 are opened (Figures 5 and 11), pressure fluid may enter said tubing string from the annular space of said casing. It is preferred to locate said ports in an equi-distantly spaced relation around said chamber and all in the same horizontal plane. However, while this valve has been shown and described with three ports, one or more ports may be used and arranged as desired. In some instances, where a great number of ports are provided, said body 34 may be elongated and the ports formed in groups of one to four ports each and each group will preferably be on a separate horizontal plane.

Each port 45 is provided with a valve cage or insert unit 46 threaded thereinto and each cage has a co-axial passageway 47 extending therethrough. The inner end of each passageway 47 is formed with a ground, tapered seat 48, so that a ball valve 49 may be mounted in the passageway of each valve cage 46, for engaging this seat and closing said passageway, whereby each of said ports will be closed. The outer end of each passageway is internally screw-threaded, so as to receive a perforated button or cap 50 to limit the outward movement of said ball valves 49 from said seats 48.

Whenever pressure fluid is introduced into said annular space of said casing string and flows through said passageways 47 and encounters said balls 49 in said opened ports 45, the passage of said pressure fluid through said opened ports will carry said balls onto their respective seats 48, thereby closing said opened ports as well as shutting off said tubing from said annular space. It will be noticed in Figures 10 and 12, that when said balls are seated so as to close said passageways, a portion thereof protrudes into said chamber 44 from said seat.

The lower end of said chamber 44 is countersunk (Figures 5 and 10), so as to form an enlarged bore 51 for receiving the upper end of a tubular mandrel 52 which has a sliding fit within said bore 51. It will be seen that a shoulder 53 is formed on the upper end of said mandrel 52 to limit the telescoping of said upper end within said bore 51. The lower end of said mandrel is internally upset, so as to form a shoulder 54 that has a reduced, depending pin 55 for telescoping within a shallow, annular sump or recess 56 in the upper surface of said lower cross plug 39. The lower end of said sump 56 is provided with one or more passageways 57 extending through said cross plug to the lower end thereof, so that a continuous passage is formed from said passageways 47 of said valve cages 46, through said chamber 44, into said mandrel 52, through said sump 56, into said passageway 57 and delivered below said cross plug body 39 and inside of said tubing string 21. The lower surface of said cross plug is provided with a socket or recess 58, that is internally screw-threaded to receive an externally screw-threaded pin 59 on the upper end of a string of auxiliary or tail pipe 60. It is preferred that this tail pipe extend down within said tub-

ing string to within a short distance of the upper end of the standing valve 25 mounted in the lower end of said tubing.

The upper end of said socket 58 is provided with one or more longitudinally extending passageways 61 extending therefrom to the upper side of said cross plug body 39, so that a continuous passage is formed from said tail pipe 60, through said socket 58, into said passageway 61, through said sleeve 31 outside of said tubular mandrel 52, into a plurality of longitudinal channels 62 extending through said valve body 34, onto the upper side of said valve 28 and within said tubing string. It is pointed out that the sump 56 and passageway 57 do not open into or connect with the socket 58 and passageway 61. The upper end of said chamber 44 is countersunk and internally screw-threaded to receive an annular sub or guide 63 having an axial bore 64 extending therethrough. The lower portion of said bore 64 is counterbored to form an enlarged bore or chamber 65 and a ground, tapered seat 66 is provided on the shoulder between said bore 64 and said chamber 65.

The upper end of said guide 63 is provided with an externally screw-threaded pin 67 for receiving a coupling member 68 having an internal chamber 69 formed therein, which is provided with a plurality of radial ports or openings 70 to provide communication between said chamber and the inside of said tubing. The upper end of said coupling member 68 is provided with an upstanding pin 71, similar to said pin 67, and having a bore 72, similar to said bore 64. This pin 71 is externally screw-threaded for receiving the threaded lower end of an upstanding, elongated guide or protector sleeve 73, that preferably extends co-axially within said tubing string 21 and spaced therefrom. The upper end of said sleeve 73 is provided with a plurality of radial ears or lugs 74 for spacing and maintaining the co-axial alignment of said sleeve within said tubing string.

It will be apparent in Figures 2, 4, 9 and 10, that only the lower portion of an actuating member or weight bar 75 depends within said sleeve 73. Nearly all wells give off a certain amount of free or formation gas from the producing formation, or other gas sands near the formation, which flows up said tubing below said cross plug body 39 and enters said duct 57 and flows therethrough, into said mandrel 52, through said chamber 44 of said valve body 34, into said chamber 69 of said coupling 65, and out through said openings 70 into said tubing above said valve. It is pointed out that this free gas is prevented from accumulating in said tubing below said valve 28 and restricting the inflow of well fluid from said formation. Also, by providing said openings 70 in said chamber 69, said free gas does not enter said guide sleeve 73, nor contact said weight bar 75, nor interfere with the operation thereof.

An elongated, cylindrical dart 76 is mounted in and extends through the lower portion of said sleeve 73, into the bore 72 of said pin 71, through said coupling member 68, into said guide 63, through the chamber 44 and into the upper portion of said tubular mandrel 52. The middle portion of said dart 76 is reduced to form an upstanding, co-axial pin or rod 77 and a flat, annular head 78 is suitably mounted near the upper end of said rod 77, so that the downward travel of said rod and said weight bar 75 may be terminated by the underside of said head 78 engaging the upper end of said pin 71. The lower portion of said dart 76 is provided with

an axial bore 79 and the upper end of said bore is provided with a plurality of radial outlet ports 80 extending from said bore to the outer surface of said dart.

As will be seen in Figures 5 and 10, a portion of said dart is externally upset or thickened, so as to form an annular boss or actuating member 81 with a tapered guide surface 82 on its upper edge. It is pointed out that the guide surface 82 engages the ball valves 49 upon the upward travel of said dart 76 and gradually forces said balls 49 off their seats 48, until said boss 81 engages and holds the balls in their open position (Figures 5 and 11). Of course, upon the downward travel of said dart, the reverse action takes place and said balls are permitted to gradually engage their seats, due to the taper of said guide surface 82. The lower end of the dart is provided with a plurality of spaced short stops or lugs 84 and a suitable coiled spring 85 is mounted within said tubular mandrel 52. The lower end of said spring rests upon the internal, upset portion or shoulder 54 of said tubular mandrel and the upper end of said spring engages beneath said stops 84, so that at all times said dart is under the tension of said spring 85. This spring serves to move said dart upwardly to open said ball valves 47, whenever said weight bar 75 is lifted. The tapered shoulder 86, formed between the lower portion of said dart and said rod 77, engages the seat 66 to limit the upward travel of said dart and to seal off the chamber 44 from said chamber 69 and the tubing above said valve 28.

Attention is called to Figures 4 and 9, wherein it will be seen that the lower end of said weight bar 75 is provided with an internally screw-threaded box 87 for receiving an externally screw-threaded, upstanding pin 88 on the upper end of a connecting sub 89 that has a similar pin 90 depending therefrom for engaging within an internally screw-threaded box 91 on the upper end of a tubular sleeve 92. The lower end of this sleeve 92 is provided with an internally screw-threaded box 93, similar to the box 91, for receiving an externally screw-threaded upstanding pin 94 of a short sub 95 which has an axial bore 96 extending therethrough. An elongated, cylindrical pin or rod 97 extends upwardly through the bore 96 of the sub 95 and the upper end of this rod 97 has a flat annular head 98 suitably mounted thereon, so that a coiled spring 99 may be interposed around said rod 97 between the underside of the head 98 and the upper end of the pin 94 and this spring is under a slight tension, so as to exert an upward force on the rod 97 through said head 98. The lower end of the rod has a screw-threaded pin 100 depending therefrom for engaging in the upper end of a sub or collar 101, similar to the sub 95, and the lower end of this sub 101 is provided with a depending, externally screw-threaded pin 102 for engaging within an internally screw-threaded box 103 on the upper end of a tubular sleeve 104. It will be seen that while the subs 101 and 95 abut, they are not connected together except by a medium of the rod 97 extending upwardly from the sub 101 through the sub 95 and the spring 99 bearing against the upper surface of the pin 94 and the undersurface of the head 98 connected to said rod 97, which makes a flexible or resilient connection between said subs. The spring 99 is of sufficient strength as to hold said subs 95 and 101 together when said weight bar 75 is being lowered into or raised

out of a well. This spring also serves other purposes which will be more fully hereinafter described.

The lower end of the sleeve 104 has an internally screw-threaded box 105 for receiving an externally screw-threaded, upstanding pin 106 on the upper end of a nipple 107. The lower end of this nipple is externally tapered at 108 for facilitating the lowering of said weight bar 75 and its entrance into the kick-off valves 26. The nipple 107 also has an axial bore 109 extending therethrough, which is of sufficient diameter as to permit the passage of a tapered head 110 mounted on the upper end of an upstanding reduced pin or rod 111. The lower portion of this pin may be thickened or upset, if desired, for adding strength thereto and the lower end of this pin is suitably mounted on the upper surface of the annular head 18 of said dart 76.

The tubular sleeve 104 is internally thickened or upset intermediate its ends and preferably medially of its length. This upset portion 112 is provided on its lower edge with a long tapered guide surface 113 and on its upper edge with a short tapered guide surface 114. A clutch assembly is positioned at this point within the sleeve 104 and co-acts with the tapered guide surfaces 113 and 114. This clutch assembly is composed of arcuate slips 115 and 116.

The lower slip segments 115 are provided on their upper portion with an external, tapered guide surface 117 to co-act with the tapered guide surface 113 of said upset portion 112 and also an internal, tapered surface 118. The lower portion of said slip segments are provided with an annular groove or recess 119 for receiving a retaining and aligning ring 120, which holds said slip segments on substantially a parallel plane, whereby they operate uniformly and as a unit. This ring may be a snap type ring or cut in segments to fit in said groove. It is pointed out in Figures 4, 9, 13, 15 and 16, that the inner surface of this ring 120 is spaced from the bottom of said groove 119, so as to allow said slip segments to expand and the outer surface of said ring acts as a guide for said slip segments 115. A coil spring 121 is mounted upon the upper end of said pin 106 and the upper end of the spring bears against the lower edge of said slip segments to support the same and exert an upward tension thereon, whereby said segments are always under an upward tension and their outer guide surfaces 117 co-act with the guide surface 113.

The lower end of the slip segments 116 are externally tapered at 122 so as to fit within the slip segments 115 and co-act with the internal guide surface 118 thereof. These slip segments 116 are provided with two spaced ribs 123, so as to form an annular groove or recess 124 therebetween for receiving a ring 125, similar to the ring 120, which serves the same purpose for the slip segments 116 as the ring 120 serves for the slip segments 115. A coiled spring 126, similar to the spring 121, is interposed between the lower end of the pin 102 and the upper side of the uppermost rib 123, so as to exert a downward tension on said slip segments 116, whereby they will always co-act with the internal guide surface 118 of said slip segments 115. The axial bore 127 of said slip segments 116 is tapered to correspond to the tapered head 110 of said pin 111, so that when said head is engaged within said slip segments 116, as shown in Figure 9,

these two surfaces are contiguous throughout their lengths. It will be seen that the head 110 flares upward, so that when said weight bar is dropped down and the head 110 is engaged within the slips 116, the weight bar is attached to said dart 76.

In operation, when said valve 28 has been assembled and made up in said tubing string 21 and said well fluid level has been lowered by the production thereof, by the use of the kick-off valves 26, or any other satisfactory means, as taught in my above-mentioned patents and co-pending applications; said weight bar 75 is suspended on the lower end of a wire line 130 extending up said tubing string and out of said casing head 22 to a suitable control mechanism (not shown). This control mechanism may be of any desired structure, although I prefer to use one of the control mechanisms such as is taught in my above-mentioned patents or co-pending applications. This weight bar 75 will be lowered approximately to the position shown in Figures 2 and 4, which is the open position of said dart 76 in said valve 28 due to the tension of said coiled spring 85. With the dart in this upper position, said ball valves 49 will be held off their seats 48 (Figures 5 and 11), so that said pressure fluid in said casing 20 above said valve 28 will force the well fluid remaining in said casing between the lowermost kick-off valve 26 and said valve 28, through the passageways 47 of said valve cages 46, into said chamber 44, through said tubular mandrel 52, into said sump 56 of the cross plug body 39, through said passageway 57 of said cross plug and into said tubing 21 below said cross plug outside of said tail pipe 60. This admitted well fluid will be forced downwardly in said tubing around the tail pipe to the lower end thereof and the pressure fluid from the annular space of said casing will follow this same path of flow. Of course, this well fluid together with the well fluid in said tubing below said valve 28, and the well fluid in said tail pipe 60 and in said valve, will be forced or displaced upwardly into said tubing above said valve and will lift the well fluid in said tubing. This upward path of flow, which also will be followed by the pressure fluid, is through said tail pipe 60, into said socket 58, through said passageway 61, into said sleeve 37 around said tubular mandrel 52, up through said longitudinal passageway 62 and out on top of said valve 28 in said tubing around said sleeve 73. The pressure fluid from said annular space of said casing, following this same path of flow as outlined for said well fluid, will lift said well fluid up said tubing string to the usual cross T 131 and into the usual flow line 132 where it is led to a separator (not shown), a storage tank (not shown), or any other suitable disposal as desired.

It is pointed out, that a perforated band or collar 133 is mounted on said upper valve body 34 between the lower end of said upper connecting collar 29 and the upper end of said sleeve 37, so as to fully cover the outer ends of said threaded ports 45 to protect the same and prevent any extraneous matter entering said passageway 47 of said valve cages 46 and clogging the same, or said perforated caps 50, or causing damage to said balls 49, or some other mechanism of said valve 28.

When said ball valves 49 are held open by the boss 81 on said dart 76, said tapered shoulder 86 is engaging said seat 66, so that the fluid entering through said passageway 47 of said valve

cages 46 will flow down around said dart, as well as into said ports 80, through said bore 79 of said dart, and out the lower end thereof.

The pin 77 on the upper end of said dart 76 is provided intermediate its ends with a plurality of elongated, longitudinal, shallow slots or grooves 135. These grooves are so placed on said pin that when said dart is in its upper position (Figure 5), the lower ends of said grooves are even with or above the upper edge of said pin 67 of said guide 63 and the upper ends of said grooves are below or in the lower portion of the bore 72 of said pin 77. When said dart 76 is in its lower position (Figure 10), the lower ends of said grooves 135 are below said seat 56 on the lower end of said bore 64 and the upper ends of said grooves extend above the upper edge of said bore 64 and into said chamber 69, whereby a passageway is thus provided from said chamber 65, through said grooves 135, to said chamber 69. This passageway thus formed will prevent the accumulation of free or formation gas in said valve body 34 and in said chamber 65 for two reasons or purposes. First, by venting said gas, said tubing below said valve 28 and said tail pipe 60 may fill with well fluid, so that upon the next actuation or opening of said valve 28, a full load or charge of well fluid is obtained; second, to prevent the accumulation of formation gas, which would interfere with the operation of said dart 76.

After the valve 28 has been operated, the normal or inoperative position of the dart 76 is its lower position (Figure 10) and this is reached by the setting down of said weight bar 75 upon said head 78 of said pin 77, so that the pressure fluid flowing through the passageways 47 closes the valves 49. It is pointed out that the slots 135 are so placed on said stem 77 of said dart 76, as to bleed the free gas from said valve body 34 when said dart is in its lower position. When said dart begins its upward travel to open said ports 45, these slots 135 are closed as soon as their lower ends enter into said bore 64 of the guide 63 and the further escape or bleeding of free gas is terminated. At this point of travel, the balance of said stem 77 between said slots and said shoulder 86 serves as a sliding plug in said bore 64, so that when said balls are pushed open by said guiding surface 82, the pressure fluid entering through the open ports 45 will assist the spring 85 in lifting said dart 76 to move the same into its upper position, to completely open said ports and seat this shoulder 86 against said seat 66.

Of course, when said weight bar is lowered until the lower end of the nipple 107 engages the upper surface of head 78, the head 110 and pin 111 will enter the bore 109 of said nipple and said head 110 will pass through said slips segments 115 and 116 and due to the matching tapers of said head and the bore 127 of said slip segments 116, said weight bar will be locked to said pin 111. Therefore, when said weight bar 75 is lifted to permit the spring 85 to push the dart 76 upwardly, this connection of said weight bar 75 to said dart may to some extent assist said spring 85 to move said dart 76 upwardly, although said spring exerts sufficient tension to readily lift said dart without any assistance from the weight bar. In fact, it is preferred that the weight bar be merely lifted so as to remove the weight of the bar from the spring 85 and permit said spring to function. When the well fluid has been lifted from below the valve 28 and

is flowing upwardly through the tubing 21, the locking of said weight bar to said dart will prevent the upwardly flowing column of fluid from having a tendency to lift said weight bar and give it a reciprocating or fluttering action thereto and to said stem. It is pointed out that by so connecting said weight bar and said dart, that any bouncing of the weight bar is eliminated and there will be no rapid opening and closing of said inlet ports or faulty operation of said valve, as well as any slack and tightening action being given to said wire line 130 which would give a bending, twisting, kinking, or unnecessary working of said wire line throughout its length; and by preventing this extra working of said wire line, a longer life thereof is obtained and expensive delays and repairs are eliminated. When the ports are closed, the free gas escapes up the well tubing and when said ports are open, said free gas will be carried with the well fluid and the pressure fluid down in said tubing below said valve 28 and up said tail or discharge pipe 60, into said tubing above said valve. It is pointed out that in initially kicking off the well, said valve 28 is in its open position (Figure 5), so that all the well fluid in said casing 20 below the lowermost kick-off valve 26 flows or is forced through said valve 28, down into said tubing below said valve and up said tail pipe, as has already been described.

If desired, the tubing below said packer 27 may be of a larger diameter than the bottom of the tubing string, in order to provide an increased fluid collecting chamber 137. Of course, this chamber will extend down to the standing valve 25, or at least below the lower end of the tail pipe 60.

Attention is called to the fact that after the well has been kicked off and is being produced, and when said flow valve 28 has been opened, the pressure lifting fluid entering said valve flows therethrough and is introduced into the upper end of said chamber 137 onto the upper surface of said well fluid therein. This well fluid is displaced downwardly in said chamber and up into said tail pipe 60, through said valve 28 and into said tubing string around said protector sleeve 73. As additional pressure fluid enters said chamber 137 and builds up the pressure therein, said pressure fluid, forcing all well fluid ahead of it, will follow the same line of flow as said well fluid. Thus when said pressure fluid reaches the lower end of said tail pipe 60 to exert its lifting force or action on the well fluid in the tail pipe, this column of well fluid is already flowing due to the above-set-out displacing action. It will be seen that the lifting force of said pressure fluid is delivered beneath an upwardly flowing or moving column of well fluid, whereby there will not be any channelling, cutting, or damaging of said well fluid, as there would be if said pressure fluid were introduced down said tail pipe and into said chamber at the lower end of said tail pipe.

In initially kicking off or beginning the production of wells, where there is a deep submergence of said bottom hole flow valve 28 in the well fluid, one of my kick-off valves 26 (not shown) may be mounted in said tubing string just above said flow valve; so that when there is too much well liquid in said fluid accumulating chamber 137, in said casing, or said well bore, and in said annular space of said casing above said packer, the flow valve 28 being normally open will admit well fluid and pressure fluid therethrough to displace well fluid from said chamber into said tub-

ing above said flow valve, until the column of well fluid in said tubing, said flow valve and said tail pipe balances the desired operating pressure of pressure lifting fluid. When the pressure or weight of the well fluid within said tubing and said flow valve balances the operating pressure fluid, of course there will be no more flow from said annular space of said casing string into said flow valve and the operator at the surface will be unable to unload or kick off the well. However, when it is determined by preliminary survey that such a condition will occur, one of my kick-off valves 26 is then mounted in said tubing string just above the upper end of said actuating weight bar 75, so that this bar could be picked up when the above-mentioned point of balance has been reached to open this kick-off valve (not shown) to admit pressure fluid at this point in said tubing string. Naturally, this kick-off valve will operate and function exactly as my other kick-off valves.

The picking up of said weight bar 75 to open this kick-off valve will admit pressure fluid to cut off the upper portion of the column of well fluid standing in said tubing. The admittance of pressure fluid through this kick-off valve will not only cut off the column of well fluid at this point, but will lift this cut-off portion or "slug" up and out of said well, as taught in my above-mentioned patents and co-pending applications, and this lifting of the well fluid will lighten the column of well fluid in said tubing, so that additional well fluid may rock or flow through said flow valve 28, until a point of balance is again reached. However, the column of well fluid may now be so light that the pressure fluid is sufficient to flow the same although if a point of balance is again reached, the weight bar 75 may again be pulled up into the kick-off valve 26 (not shown) and as soon as the cut-off portion or slug of well fluid reaches the surface, said weight bar is again lowered to close said kick-off valve, so that additional pressure fluid may build up in said tubing above said flow valve. This operation may be repeated as often as is necessary and until the desired operating pressure can handle the well fluid produced by said producing formation, and when this condition occurs, the pressure fluid will flow through said valve into said chamber, onto the upper surface of the well fluid in said chamber and lift the same out as has already been hereinbefore outlined. When the pressure fluid has lifted the well fluid from said chamber and said tail pipe up and out of said tubing, the weight bar 75 is dropped onto the flat head 78 of said stem 77 (Figure 10) to move said dart 76 downwardly and release the balls 49, so that the pressure fluid entering said passageways 47 will carry said balls onto their seats 48, thereby closing said passageways and terminating the admittance of pressure fluid into said flow valve 28.

When the weight bar 75 is dropped down onto the head 110 of said pin 111, the spring 126 will give and permit the slip segments 116 to retract to permit the entrance of said head 110 into and through said slip segments because they will expand as they move upwardly due to the tapered guide surface 122 co-acting with the tapered guide surface 118 of said slip segments 115. This retraction and expansion of said slip segments 116 will permit said head 110 to pass through said slip segments 116 and after said head has passed therethrough, the spring 126 will force said slip segments back to their original position, which locks said head therein and connects said weight

bar 75 to said dart 76. Thus, this spring becomes a lock or holding spring.

When it is desired to disengage the weight bar 75 from the dart 76, said bar is pulled upwardly by means of the wire line 130 and due to the tension of the spring 121, said spring 99 will be substantially completely collapsed before said slip segments 115 move downwardly against the tension of said spring 121. The slip segments 116 will move downwardly with the slip segments 115 until the undersurface of the lowermost rib 123 contacts the upper guide surface 114 of the upset 112 or substantially so, and due to the tapered guide surface 113 being greater than the tapered surface 118, the slip segments 115 will expand faster than the slip segments 116, or rather the slip segments 115 move outwardly at a greater rate than they move downwardly; so that with a slight downward movement, said slip segments 115 and the lower portion of said slip segments 116 expand sufficiently to allow the slightly tapered head 110 to slide downwardly through said slips segments 115 and 116. As soon as said head 110 has moved out of the bore 127 of said slip segments 116, said slip segments are free to move upwardly under the tension of said spring 121, back to their original position, as shown in Figure 4. Immediately upon the release of said head 110 from said slips segments 115 and 116, the spring 99 expands to lift the head 98 and draw the nipple 107, the sleeve 104 and the sub 101 upwardly, until said sub abuts the underside of the sub 95 and the parts will be approximately in the position shown in Figures 4 and 5.

Attention is called to the fact that the protector sleeve 73 is provided throughout its length with a number of holes or perforations 140 drilled therein so that any sand or foreign matter falling into said sleeve would be washed out and the accumulation thereof in said sleeve prevented, whereby any interference with the proper operation or movement of said weight bar and said dart is eliminated. The spring 99 also serves to form a resilient connection between the weight bar proper 75 and the overshot assembly mounted on its lower end, so that should too great a pull be exerted on the wire line when it is only desired to open the valve 28, the spring 99 will partially collapse and permit the dart 76 to be operated without pulling the head 110 from said slips segments 115 and 116. Thus, it will be seen that the spring 99 serves the two purposes of forming a resilient connection between the weight bar and the overshot to allow for any inaccuracy in the operation of the wire line 130, as well as to hold the sub 101 and its parts depending therefrom securely to the lower end of the weight bar when the same is suspended or moving in the well tubing. Attention is called to the fact that the weight 75 may be connected to and released from the head 110 of said pin 111 of the dart 76 as often and when desired, without any difficulty or damage to any of the parts. Also, this invention solves the problem of preventing the "bouncing" of the weight bar and the breakage of the supporting line.

It is pointed out that various changes and modifications of the invention may be made as is necessary to accommodate the numerous and various producing conditions presented without departing from the spirit of the invention.

What I claim and desire to secure by Letters Patent is:

1. In a well liquid flowing apparatus, the combination with a lifting fluid supply in a well liq-

uid supply, of a valve normally open to admit lifting fluid to said supply and having means for conducting it to said supply of well liquid for displacing said well liquid, means for conducting the displaced well liquid from said supply to the surface of the well, means operable from the surface of the well for actuating said valve to said normal open position or to move to permit said valve to shut off the admission of lifting fluid, surface operated means for actuating said surface operable means, and means for releasably connecting said surface operated means to said surface operable means.

2. A valve for a well fluid lifting apparatus including, an enclosure having a passage therein, inlet means for admitting lifting fluid to said passage, means for closing said passage above said inlet means, said passage closing means opening said inlet means when closing said passage, means for conducting lifting fluid downward from said passage, means operable from the surface of the well for moving said passage closing means to open the passage above said inlet means and permit the closing of said inlet means, and means for releasably connecting the surface operating means to said passage closing means.

3. A valve for a well fluid lifting apparatus including, an upright enclosure having a passage therethrough and a fluid outlet, a valve seat below said outlet, an inlet valve in the enclosure below said seat, spring actuated means having a valve member engaging said seat and also engaging said inlet valve to hold it open, means operable from the surface of the well for depressing said spring actuated means to unseat said member and to release the inlet valve, and means for releasably connecting said surface operated means to said spring actuated means.

4. A valve for a well fluid lifting apparatus including, an upright enclosure having a fluid passage therein, an inlet valve for admitting lifting fluid to said passage, spring actuated means engaging said inlet valve and holding it open, means operable from the surface for depressing said spring actuated means to release said inlet valve, and means for releasably connecting said surface operated means to said spring actuated means.

5. In a well liquid lifting system the combination with, an eduction conductor for conveying the liquids from a well, means for accumulating a column of well liquid, means for providing a lifting fluid conductor around the eduction conductor, of means operable from the surface of the well to admit lifting fluid and conduct said lifting fluid to said well fluid, surface operated means for actuating the fluid admitting means, means for directing said admitted lifting fluid downwardly upon said column of well liquid to displace said liquid upwardly into said eduction conductor, and means for mechanically and releasably connecting said surface operated means to said fluid admitting means, whereby said connection may be made without removing the fluid admitting means from the well.

6. In a well fluid lifting system the combination of, a packer mounted in the well, a well liquid discharge pipe having its inlet a substantial distance below the packer disposed around said pipe to provide a column of well liquid, flow means having a lifting fluid inlet disposed above said packer and a conductor for conveying the admitted fluid below said packer for displacing the well liquids downwardly, whereby said liquids

are discharged through said pipe, means for maintaining the inlet open, surface control means for releasing said maintaining means, whereby the pressure lifting fluid inlet may shut itself off, and means for releasably connecting said surface control means to said maintaining means.

7. In a well fluid lifting system the combination of, an eduction pipe, a packer disposed around said pipe, a well liquid discharge pipe having its inlet a substantial distance below the packer to receive a column of well liquids, flow means having a lifting fluid inlet disposed above said packer and a conductor for conveying the admitted fluid below said packer for displacing the well liquids downwardly around said discharge pipe to its inlet, whereby the well liquids are expelled through the discharge pipe into the eduction pipe through which it is lifted to the well surface, means having a connection with the lifting fluid inlet for holding said inlet open, surface operated means for disengaging the holding means from said lifting fluid inlet to permit the pressure lifting fluid to close said inlet, and means for releasably connecting said surface operated means to said holding means, whereby said surface operated means may be connected or released from said holding means when desired.

8. In a well fluid lifting system the combination of, an eduction pipe, a packer disposed around said pipe, a well fluid discharge pipe having its inlet a substantial distance below the packer to receive a column of well liquids, flow means having a lifting fluid inlet disposed above said packer and the admitted fluid below the packer for displacing the well liquids downwardly around said discharge pipe to its inlet, whereby the well liquids are expelled through said discharge pipe into the eduction pipe through which it is lifted to the well surface, means having a connection with the lifting fluid inlet for holding said inlet open, surface operated means for disengaging the holding means from said lifting fluid inlet to permit the pressure lifting fluid to close said inlet, the column of well liquids accumulating in said discharge pipe while said inlet is closed, means for releasably connecting said surface operated means to the holding means, whereby said surface operated means may be connected to and disengaged from said holding means when desired, and means for venting any free gas while the liquids are accumulating and said inlet is closed.

9. A flow valve for a well fluid lifting system having a well flow pipe in a well casing including, a body adapted to be connected into the flow pipe and having a bore and flow channels extending therethrough for conveying fluid, an inlet port in said body connected to the bore for admitting a lifting fluid to the bore to displace well fluid below said body through the flow channels thereof into said flow pipe, a closure member for said port, means mounted in said bore for actuating said closure member, means operated from the surface for operating the actuating means, and means carried thereby for releasably connecting said surface operated means to said actuating means.

10. In a well fluid flowing device having a string of well tubing suspended in a well includ-

ing, an elongate body having connecting collars on each end thereof for connecting said body in the well tubing string, an axial bore extending through said body so as to form a passageway 5 with said well tubing, a radial port in the upper portion of said body, a valve for said port adapted to be operated from the bore of said body, operating means movable in said bore for operating said valve, an elongated actuating member depending in said well tubing for actuating said operating means, means carried by said actuating member for releasably connecting the same to said operating means, whereby said actuating member may be connected to or released from said operating means when desired, and a wire line depending in said well tubing for suspending said actuating member and said connecting means and controlling the operation of said actuating member and said connecting 15 means.

11. As a sub-combination in a well fluid lifting system wherein a flow valve is adapted to be connected in a well flow pipe and has an inlet port and an operating means for said valve, an actuating member for said operating means, a connecting and releasing device carried by and supported from the actuating member, a resilient connection between said device and said actuating member, the connecting and releasing device 20 including a tubular housing for receiving a connecting member on the operating means, a clutch assembly in said housing mounted on resilient means, said clutch assembly releasably engaging said connecting member, whereby said actuating member may be connected to and released from said connecting member when desired.

12. A system of flowing well fluid in a well having a well casing and a well tubing within the casing including, a supply of lifting fluid in 40 said casing, a series of valves connected to the tubing for admitting lifting fluid from said casing into said tubing, surface controlled means reciprocably mounted in said tubing for actuating said valves, an operating member for the lowermost valve and a tool carried by the actuating 45 means for mechanically and releasably connecting to the operating member, whereby said means and tool may be disengaged from the lowermost valve whenever it is necessary to actuate one or all of the valves thereabove.

13. A system of flowing well fluid in a well having a well casing and a well tubing within the casing including, a supply of pressure lifting fluid in said casing above the liquid level therein, unloading valves connected to the tubing, means 55 controlled from the top of the well for admitting lifting fluid from said casing into said tubing, means connected to said tubing for providing a column of well fluid, means for delivering the admitted lifting fluid to said column of well fluid 60 below the point of admission to elevate the same in said tubing, and means controlled from the surface for operating the unloading valves and controlling the lifting fluid admitting means and mechanically and releasably connected to said 65 admitting means, whereby said operating means may be disengaged from said admitting means whenever it is necessary to actuate said unloading valves.

JEDDY D. NIXON.
